F. B. JOHNSON,

MASTER VIBRATOR.

APPLICATION FILED JAN. 28, 1913

1,086,718.

Patented Feb. 10, 1914.

UNITED STATES PATENT OFFICE.

FREDERICK B. JOHNSON, OF KANSAS CITY, MISSOURI, ASSIGNOR OF ONE-HALF TO
GEORGE STEINHORST, OF KANSAS CITY, MISSOURI.

MASTER-VIBRATOR.

1,086,718.

Specification of Letters Patent.

Patented Feb. 10, 1914.

Application filed January 28, 1913. Serial No. 744,667.

To all whom it may concern:

Be it known that I, FREDERICK B. JOHNSON, a citizen of the United States, residing at Kansas City, in the county of Jackson and State of Missouri, have invented certain new and useful Improvements in Master-Vibrators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This specification relates to vibrators, and more particularly to a master vibrator for use in circuit with a plurality of vibrating induction coils and has for its principal object to provide a device whereby a master vibrator may be substituted for the vibrators of each induction coil, where a low tension magneto may be connected in circuit with the induction coils and where a battery may be connected in circuit with the induction coils.

In accomplishing this object I have provided the improved details of structure hereinafter described and illustrated in the accompanying drawings, reference now being had to the accompanying drawings, wherein:

Figure I is a perspective view of a vibrator constructed according to my invention. Fig. II is a perspective view of the device, the casing being removed for better illustration. Fig. III is a sectional view on the line III—III, Fig. II. Fig. IV is a detail perspective view of a portion of the lower corner of the device, showing a few of the contact brushes and the switch bearing. Fig. V is a wiring diagram showing the several circuits.

Referring more in detail to the parts:—1 designates a casing of any suitable material, 45 having a hinged lid 2, attaching lugs 3, and an arc-shaped boss 4 provided with an elongated slot 5 through which the switch lever 6 is projected, the face of the boss being marked to designate the battery, magneto, 50 off and master vibrator, which parts will presently be described.

Secured within the casing, by means of screws 7, is a plate 8 and shelf 9, of insulating material, on which parts of the vibrator 55 are mounted. Spaced from the shelf 9 by

means of a curved metal piece 10 is a piece of insulating material 9' which is also secured to the plate 8 and supports an electromagnet 11, the case 12 of which projects through the shelf 9 and beneath the vibrator 60 arm 13 of the master vibrator 14.

In detail the master vibrator 14 comprises, in addition to the arm 13, a spring 15 rigidly secured to said arm and held in an adjusted position by means of a screw 16, a contact 65 point 17 which is adapted for coöperation with a contact point 18 on an adjusting screw 19 that is mounted in a slotted arm 20 secured to plate 8, and a clamping screw 21. Also rigidly mounted on arm 13 is a pin 22 70 which projects through an aperture 23 in the spring leaf 15 and with which a coil spring 24 is connected, the opposite end of the spring being connected with a screw 25 slidably mounted in a bracket 26 on the shelf 75 9 and provided with a thumb nut 27 whereby the tension of the spring may be varied to draw the arm 13 into the V slot 28 of bracket 26 and the contact point 17 against contact point 18.

Pivotedly mounted in the insulating member 9' and in a bracket 29 is a cylinder 30, of insulating material, which carries the switch lever 6 heretofore mentioned. Cylinder 30 has a plurality of longitudinal 85 grooves 31, all but one of which have metal inserts 32 of different lengths, dovetailed into the body of the cylinder. Immediately back of the cylinder 30, and secured to the plate 8 by means of screws 33, are a plurality of brushes 34 which angle outwardly and yieldingly take into grooves 31 and contact with the metal inserts or rest in the barren groove indicated by "Off" on the outside of the casing.

At one side of the coil 11 and cylinder 30 is a condenser 35 which is shunted in between the vibrator arm 13 and adjusting screw 19 to reduce the effects of self-induction in the coil 11 and thus prevent needles 100 sparking at the contact points 17—18.

In the diagram illustrating the use of my improved vibrator, I have indicated its connection with a four cylinder automobile engine, the several devices shown in the wiring 105 diagram being peculiar to the ignition systems of engines of this class. Referring to the wiring diagram:—36 designates a timer or contact maker of any ordinary construction adapted for a four cylinder engine, A, 110

B, C and D induction coils, each comprising soft iron coils 37 provided with primary and secondary windings 38 and 39 respectively, vibrator arms 40 and adjusting screws 41. 5 42 designates a low tension magneto, 14 the master vibrator, 35 the condenser, 34 the brushes individually designated *a*, *b*, *c*, *d*, *e*, *f*, *g*, and *h*, 43 a battery and 44 spark plugs. In following up the several circuits, 10 10 pose switch lever 6 is moved so as to lie opposite the abbreviation "Bat.", the result will be as follows: One of the metal inserts will connect the brushes "a" and "b" together and current will flow from battery 15 43 to the ground which is the engine frame, from the ground to the timer 36 and thence to the primary windings of one of the coils A, B, C or D, through adjusting screw 41, vibrator arm 40, brushes "b" and "a" and 20 back to the battery. This sets up a high tension current in the secondary coil 39, one end of which is grounded through the timer 36 on the engine frame, the other end being connected to the spark plug 44, a portion of 25 which is grounded and adapted to produce a spark. If the switch lever is moved opposite the abbreviation "Mag." the circuit is the same except that the current flows from the magneto 42 to the ground and so on. If, 30 however, the switch is brought opposite the abbreviation "M. V." the whole system changes. The vibrators of the several induction coils cease to operate and a master vibrator is introduced into the main current 35 so as to rapidly interrupt the current in flowing through any one of the primary coils 38. The circuit just referred to starts from magneto 42, flows to the ground, from the ground to the timer 36, to the primary coil 38 and to the brush "d." From brush "d" which has been connected to the brush "h" by one of the metal inserts 32 the current 40 flows through the said insert and brush "h" to the coil 11, to the contact screw 19, vi-

brator arm 13 and back to the magneto, the 45 condenser 35 being shunted in between the vibrator 13 and contact screw 19 for the purpose heretofore referred to.

It is apparent that a device of this character is particularly adapted for use on 50 automobiles, where the induced current is of high voltage and the vibrators so delicate that they often become inoperative owing to the "fitting" of the contact points.

With a device of this character a person 55 may start the engine on the battery as is customary, and switch to the magneto. If, for any reason, the vibrators of the separate coils are not adjusted perfectly, causing the cylinders to "miss," the switch may be 60 turned so as to bring the master vibrator into the current so that the engine may be run without interruption of delay and the other vibrators adjusted at leisure.

Having thus described my invention, what 65 I claim as new therein and desire to secure by Letters-Patent, is:

1. In a device of the character described, a plurality of induction coils each having individual vibrator mechanism, a master 70 vibrator, and a switch for simultaneously disconnecting said individual vibrator mechanism and introducing said master vibrator.

2. In a device of the character described, a plurality of inductor coils, each having 75 individual vibrator mechanism, means for simultaneously introducing said coils into an electric circuit, a master vibrator, and a switch for simultaneously disconnecting the individual vibrator mechanism from and introducing the master vibrator into the electric circuit.

In testimony whereof I affix my signature in presence of two witnesses.

FREDERICK B. JOHNSON.

Witnesses:

LEWIS L. MILLER,
LETA E. COATS.
